UNITED STATES PATENT OFFICE.

ELMER J. BLISS, OF BOSTON, MASSACHUSETTS.

DEVICE FOR MEASURING FEET.

1,426,143.

Specification of Letters Patent. Patented Aug. 15, 1922.

Application filed August 7, 1918. Serial No. 248,717.

To all whom it may concern:

Be it known that I, ELMER J. BLISS, a citizen of the United States, and resident of Boston, county of Suffolk, State of Massachusetts, have invented certain new and useful Improvements in Devices for Measuring Feet, of which the following is a specification.

This invention relates to the art of fitting 10 shoes to the human foot. Its primary purpose is to provide a simple, convenient and absolutely reliable device for readily ascertaining or indicating the length size and the width size of a shoe required to properly fit 15 the foot that is being measured while in an expanded position normally supporting the weight of the body.

It is well known that the human foot 20 when supporting the weight of the body expands both in length and width and that feet of different types will expand in different ratios. The size stick commonly used in shoe stores for measuring the length of feet is not adapted to measure the foot when expanded by the weight of the body and it is 25 the custom to make a more or less arbitrary allowance for such expansion.

The present invention is especially adapted 30 to indicate the size measurements when the foot is in the expanded position bearing the weight and consists, generally speaking, in the combination of a foot supporting platform provided with movable side gauges adapted to come into contact with opposite 35 sides of the ball portion of the foot and being correlated with a width-indicating device which registers or indicates the proper width of shoe required for the foot being measured. An additional feature consists in 40 the provision of an adjustable toe gauge combined with a properly marked scale on the platform or base so arranged as to correctly indicate the required length of the shoe. In this case the toe gauge is made to 45 give two length measurements, one corresponding to the actual length measurement of the foot and the other corresponding to the size length of the shoe required to fit it.

These and other features of the invention 50 will be particularly explained and disclosed in the following specification and will be defined in the claims annexed hereto.

In the accompanying drawings I have illustrated a convenient form of construction

and arrangement embodying the principles 55 of this invention in which

Figure 1 is a plan view of the complete device;

Figure 2 is a side elevation thereof;

Figure 3 shows the details of the side 60 gauge supporting brackets and the connecting registering link which lie beneath the platform as indicated in dotted lines of Figure 1.

In the practice of my invention according 65 to the form illustrated, I provide a base or platform *a* for supporting the foot provided with legs *a'* to raise it slightly above the floor in order to leave clearance for the movement of the parts underneath. The 70 heel portion of the platform is preferably slightly raised and has at the back end a projecting lug *a⁴* to form a gauge or rest for accurately positioning the heel of the foot. The elevation of the heel portion of 75 the base corresponds approximately with the elevation of the heel of the foot that is caused by the heel of the shoe in order that the posture of the foot when being measured may approximate the posture of the foot 80 when wearing the shoe. At its forward end the base is provided with a boss *a³* bored longitudinally to receive the slide rod *b³* which carries at its rear end a plate *b'* and a projecting lug or finger *b²* adapted to 85 move over a graduated scale *b* marked on the base itself at proper distances or intervals to shoe size lengths and fractions thereof.

The plate *b'* is arranged to touch the extreme tip of the great toe and serves to register with the numeral on the scale that indicates the actual size length of the foot as it supports the weight. The forward end of the tongue or finger *b²* serves to indicate the 95 size length of the shoe appropriate to fit the foot being measured.

On the opposite sides of the base along the ball portion of the foot are mounted two 100 movable side gauges adapted to have light contact with the opposite sides of the ball portion of the foot each gauge being capable of movement independently of the other so that if one side gauge comes to rest against one side of the foot before the other gauge 105 reaches its position of contact the other gauge will be free to move until it also forms a gauging contact with the foot.

Any convenient way of mounting the gauges may be employed and in the form shown in the drawings this is accomplished as follows. On the under side of the base 5 or platform *a* is formed a lug *a*² transversely bored to receive a gauge supporting rod *c*. For supporting the right hand gauge a bracket *e* is provided which has perforated lugs *e*¹ *e*² through which passes the rod *c* 10 and by means of which the bracket *e* has a sliding support on said rod. At its right hand end bracket *e* is provided with an upwardly turned flange or web *e*³ carrying the horizontal plate *e*⁴ whose inner edge terminates in an upwardly extending flange *e*⁵ 15 which forms the contact member for engaging the adjacent side of the foot.

In a similar manner a bracket *d* provided with lugs *d*¹, *d*² perforated to receive the rod 20 *c* forms a sliding support for the horizontal plate *d*⁴ through the medium of the vertical web *d*³. The upwardly extending flange *d*⁵ forms a contact member for engaging the adjacent side of the foot.

25 On the under side of plate *d*⁴ is formed a pin or boss *d*⁶ and on the under side of the bracket *e* near its outer end is formed a similar lug or pin *e*⁶ and these two lugs are connected by means of a helical tension spring 30 *g* which tends to automatically draw the two gauges toward each other to bring them lightly into contact with the opposite sides of the ball portion of the foot, while at the same time allowing the gauges to be moved 35 farther apart in order to receive between them the foot to be measured.

The width-indicating device as shown 40 comprises a cross-connecting link *f*⁴ pivotally connected with the gauge member *e*⁴ as shown at *f*⁵ and having at its opposite end a pivotal connection with an arm *f*³ that is secured to the lower end of a short vertical shaft *f* which carries at its upper end both the plate *d*⁴ and the pointer or indicator *f*¹ 45 whose free end travels along a graduated scale marked on the member *d*⁴ to correspond with the standard width sizes of shoes.

A handle *f*² serves to rotate the shaft *f* in a clockwise direction to bring the pivotal 50 connection between the short arm *f*³ and link *f*⁴ into line with the two centers *f*, *f*⁵ in which position the link members are on a dead center, thereby preventing the tension spring *g* from drawing the two gauge members toward each other. When the foot is 55 positioned on the base, the turning of the handle *f*² in a reverse or contra-clockwise direction moves the pivotal joint away from the dead center and allows the tension spring 60 to act in normal fashion to bring each side gauge into close contact with the corresponding side of the foot in which position the pointer or indicator *f*¹ will correctly indicate the appropriate size width of the shoe required. 65

Beside indicating the length measurement of the foot and the length size of the appropriate shoe therefor, the toe gauge may serve as an indicator for ascertaining or showing the appropriate size of stocking required to 70 fit the foot being measured. To this end I provide a stocking scale *n* whose graduations are correctly positioned with relation to the right hand pointer *b*⁶ to indicate the appropriate size of stocking when the toe gauge 75 plate *b*¹ is in contact with the extreme tip of the great toe. It will therefore be seen that by merely sliding the toe gauge into contact with the great toe there is automatically indicated readings for showing the length 80 measurement of the foot and the appropriate length of stockings and shoes therefor.

As is commonly understood in the art of shoe making and last making the units of width measurement or the width sizes corresponding to the actual width measurement varies progressively with each increase in the length of the foot. For example, the width distance corresponding to a B width in a 85 No. 9 last would be just the same in actual measurement as width A in a No. 10 last or width C in a No. 8 last. To meet these conditions and secure correct width size indications on the machine in accordance with the different lengths of feet to be measured, 90 provision should be made whereby variations in the length sizes of feet being measured should be attended with the appropriate variations in the width size indicated. That is, for each increase in length size the width 95 indicator should indicate one width narrower for the same actual width distance separating the side gages on any selected transverse plane or should indicate the same width size if the gages are moved farther 100 apart by a distance equal to one width size.

In the form of my invention illustrated in the drawings this is conveniently accomplished by employing side gages which diverge toward the toe end of the machine 110 at the appropriate angle to compensate for the increase in size of the width units in correlation with the increased distance from the heel gage or stop. This principle by which the width indications are varied in 115 correlation with the different lengths of feet constitutes an important feature of my present invention.

What I claim is:

1. A device for measuring feet embracing 120 in its construction a foot supporting base provided with heel-positioning means combined with a pair of side-gauging members arranged on opposite sides of the ball portion of the base each of which is capable of movement independently of the other and a width-indicating device operatively interconnected with both said side members to indicate the width size of shoe for the foot being measured according to the width of 125 130

the space between said gaging members, substantially as described.

2. In a foot measuring device the combination of a foot supporting base, side gaging members mounted to have transverse movement toward and away from each other across said base and supported against movement longitudinally of said base, a width indicating device operatively combined 10 with both said side gaging members in a manner adapted to permit unequal movement of said members while indicating in width sizes the total separation of said side gaging members, substantially as described.

15 3. In a foot measuring device the combination with a foot supporting base, of foot positioning means, oppositely movable side gaging members supported on fixed portions of the base, one of said side gaging members 20 being provided with a graduated scale, a movable pointer arranged in proximity to said scale and means connected with both said side gaging members and acting conjointly to shift said pointer along said scale 25 to indicate the proper width size of a shoe in accordance with the width of the entire space separating said side gaging members, substantially as described.

4. The combination with a foot supporting base, side-gauging members each of which is laterally movable toward or away from the other to gauge the width of an interposed foot, a width-size indicating scale formed on one gaging member, a movable 30 pointer arranged in proximity to said scale and moved to different portions of the scale by the combined movement toward or away from each other of said side-gauging members, substantially as described.

40 5. In a foot measuring device the combination of a foot supporting base provided with a heel gauge and an adjustable toe gauge, oppositely disposed side-gauging members movable toward each other to 45 make a gauging contact with the opposite sides of the interposed foot, and having a width-indicating pointer and scale, and a link connecting the side members and the pointer for causing the pointer to indicate 50 the appropriate width of shoe according to the extent of separation of the side-gauging members from each other, substantially as described.

6. The combination of a foot supporting 55 base, a transverse guide rod, two side-gauging members slidably mounted on said guide rod one of said side-gauging members carrying a pivoted pointer and a width-indicating scale, a link interconnecting said 60 pivoted pointer with the opposite side-gauging member, substantially as described.

7. The combination of a foot supporting base provided with means for gauging the length of the foot being measured, oppositely 65 disposed movable side members for engag-

ing opposite sides of the foot, means for normally drawing said side members toward each other, one of said side members being provided with a width-indicating scale, and a pivoted pointer arranged to move over the 70 scale, a connecting link connecting the pointer with the opposite side member whereby by the movements of the side members toward or away from each other causes a corresponding movement of the pointer along 75 the scale, substantially as described.

8. The combination of a foot supporting base provided with suitable heel and toe gauges, width-indicating gauging members mounted on opposite sides of the base, one 80 of said members having a movable pointer and its co-ordinated width-indicating scale, a pointer-actuating link extending from one side member to the other beneath the base and serving, when the side members are extended apart, to maintain them in extreme position of separation, and a spring normally tending to draw said side members toward each other, substantially as described.

9. In a foot measuring device the combination of a foot-supporting base having a length-indicating scale, a heel-positioning gauge and a length size toe gauge slidably mounted at the forward end of said base to move along said graduated length scale 95 marked on the base, said toe gauge being provided with two gauge-registering portions one for indicating the actual length measurement of the foot and the other for indicating the appropriate size length of the 100 shoe to fit such foot, substantially as described.

10. In a foot measuring device the combination of a foot-supporting base provided with a heel-positioning gauge at its rear 105 end and having two graduated scales extending longitudinally through the fore-part, one scale being marked to indicate length sizes of shoes and the other scale being marked to indicate length sizes of stockings, 110 and a longitudinally adjustable gauge arranged to abut against the tip of the toe provided with gauge registering indicating surfaces correlated with said scales to show the stocking size and the shoe size appropriate to said foot, substantially as described.

11. A foot measuring device embracing a foot supporting base provided with a heel-positioning gauge at its rear end and 120 an adjustable toe gauge arranged in co-ordination with two length size scales extending through the toe part of the base to indicate the length measurements of the foot and of the shoe and of the stocking appropriate to fit said foot, substantially as described.

12. In a foot measuring device, the combination of a foot supporting platform having a heel positioning stop, opposed up- 130

- wardly projecting width gauge members mounted to have lateral movement independently of each other, means normally acting to draw said gauges toward each other 5 into gauging contact with the opposite sides of an interposed foot at the ball portion thereof, and means coordinated with said gauge members for indicating the size width measurements in correct correlation with the 10 length and width of the foot being measured, substantially as described.
13. In a foot measuring device, the combination of a foot supporting platform having a heel positioning stop, independently 15 movable width gauging members automatically drawn into gauging contact against the opposite sides of an interposed foot, means for indicating the width size of an interposed foot in direct coordination to the 20 length of the foot said indicating means embracing a width size scale and a cooperating indicator, said width gauging members, said
- indicator and said scale being coordinated to indicate on said scale the width size in correct correlation with the length of the 25 foot, substantially as described.
14. In a foot measuring device, the combination of a foot supporting platform, laterally movable width gauges projecting upwardly above the level of said platform and 30 normally drawn into gauging contact with the opposite sides of the foot, width-size indicating means coacting with said width gauges to indicate the width of an interposed foot in accordance with the actual 35 distance separating said gauges and with the length of the foot, the width gauging faces of the gauge members diverging forwardly to correlate the width measurement to the length of the foot, substantially as 40 described.

In witness whereof, I have subscribed the above specification.

ELMER J. BLISS.
